Patented Nov. 5, 1963

196,811

MEAT MIXING MACHINE

William Lasar, 2540 E. 114th St., Los Angeles, Calif.

Filed Jan. 14, 1963, Ser. No. 73,169

Term of patent 14 years

(Cl. D55—1)

FIGURE 1 is a perspective view of a meat mixing machine showing my new design;

FIGURE 2 is a side elevational view thereof;

FIGURE 3 is an end view thereof showing the end opposite the end visible in FIGURE 1; and

FIGURE 4 is a top plan view thereof.

I claim:

The ornamental design for a meat mixing machine, substantially as shown.
